UNITED STATES PATENT OFFICE.

ANTHONY CLARK, OF PARKERSBURG, WEST VIRGINIA.

SEAL HASP-LOCK.

SPECIFICATION forming part of Letters Patent No. 447,664, dated March 3, 1891.

Application filed November 6, 1890. Serial No. 370,467. (No model.)

To all whom it may concern:

Be it known that I, ANTHONY CLARK, a citizen of the United States, residing at Parkersburg, in the county of Wood and State of 5 West Virginia, have invented new and useful Improvements in Seal Hasp-Locks, of which the following is a specification.

This invention has for its object to provide a novel, simple, efficient, and economical seal 10 hasp-lock of such construction that the parts are preserved in correct locking position and even though the door and door-frame expand or contract. To accomplish this object my invention involves the features of construction, 15 the combination or arrangement of devices, and the principles of operation herein-after described and claimed.

To enable others skilled in the art to understand and practice my said invention, I 20 will proceed to describe the same in detail, reference being had to the accompanying drawings, in which—

Figure 1 is a face view or elevation of a car 25 and car-door equipped with my invention. Fig. 2 is a detail perspective showing the metallic portions of the lock, the same being shown in their normal relations to each other.

In the said drawings, the reference-numeral 1 denotes the door-post or part of the door-frame of a car or other similar structure, 30 while the numeral 2 denotes the car-door. Set within a suitable recess in the door-post or frame 1 is a metallic plate 3, preferably formed of steel and having any preferred 35 shape, the form shown being rectangular. This plate is secured within its recess by bolts 4, and through the same pass the arms of a staple 5, which may penetrate the plate and be riveted upon the rear face thereof, or, if 40 preferred, may pass entirely through the door-post and be secured in any preferred manner.

Upon the door 2 is mounted the hasp-plate 6, consisting of a metal plate of suitable thickness having an eye 7 at one end which 45 engages an eye 8 in a bolt 9, passing through one of the beams or braces of said door. At its other end this plate 6 is provided with a slot 10, which is adapted to engage the staple 5, the length of said slot being in excess of 50 the width of the staple.

Upon the hasp-plate 6 is mounted a pivot 12, having a flat head 13, and upon said pivot is mounted a locking-plate 14, having an

elongated slot 15, which receives the pivot-pin, whereby a longitudinal movement or adjustment of the locking-plate upon said pin is permitted. Upon its end which lies adjacent to the locking end of the hasp-plate is formed a depending bolt 16, which may be engaged with or disengaged from the staple 60 by entering or withdrawing it from the same, the slot 15 permitting a sufficient longitudinal movement to permit this engagement and removal. Immediately above the point of union between the said bolt and the 65 locking-plate is formed an outwardly-projecting lug 17, having an opening 18, said lug resting upon the staple in such position that the wire or wires of the seal may be passed through its opening and through the staple 5. 70 The wire is then passed through the lead or other seal 19, with which they are connected permanently in any manner preferred. It will be observed that by this construction I not only provide a strong and simple lock 75 which cannot be tampered with without destroying the seal, but I also make ample provision for a perfect fit of the hasp-plate over the staple and the engagement of the locking-plate with the latter under any shrinkage or 80 expansion of the car-door or of the door-frame. Moreover, the slot in the locking-plate permits the longitudinal movement of the latter upon the pivot-pin on the hasp-plate, whereby the straight or substantially 85 straight bolt 16 may readily be withdrawn from and re-engaged with the staple 5.

What I claim is—

A seal hasp-lock consisting of a staple, a hasp-plate having at one end a slot for the 90 passage of the staple, and a locking-plate having a pin and elongated slot connection with the hasp-plate and provided with a pendent bolt, and a lateral lug arranged in juxtaposition to the bolt and having an orifice there-through for the passage of a seal-wire through the lug and the staple, whereby the bolt cannot be lifted from the staple without breaking the seal, substantially as described. 95

In testimony whereof I have hereunto set 100 my hand and affixed my seal in presence of two subscribing witnesses.

ANTHONY CLARK. [L. S.]
